UNITED STATES PATENT OFFICE.

ALBERT D. JUDD, OF NEW HAVEN, CONNECTICUT.

DESIGN FOR A DRAWER-PULL.

Specification forming part of Design No. **7,463**, dated June 2, 1874; application filed January 30, 1874.
[Term of Patent 7 years.]

To all whom it may concern:

Be it known that I, ALBERT D. JUDD, of New Haven in the State of Connecticut, have invented or produced a Design for a Drawer-Pull, of which the following is a specification:

In this drawer handle or pull the finger portion *a* is shaped as a section of a cylinder, or nearly so, as seen in Figure 2, and the ends *b* are nearly flat, and provided with attaching flanges *c* of the ornamental configuration, shown in the perspective view, Fig. 1. Above the pull is an ornamental frame in line at the back with the back surface of the pull, so as to set against the drawer with an opening at *e*, with rounded ends, through which the name-card placed behind it can be seen. There is a top scroll ornament, *f*, and end ornaments *g* also formed as scrolls, as represented in Fig. 1.

Upon the surface of the pull *a* there are the ribs forming panels and scroll-work ornaments, as at *k*, and also foliated ornaments at *l*, shown in Fig. 1.

I claim as my invention—

1. The design of the shape and configuration of the frame with the rounding ends to the opening therein, and the scroll ornaments *f* and *g* of the configuration represented.

2. The design of the ornamental scroll-work *h*, ribs, and foliated ornaments *l* upon the surface of the pull *a*, as represented.

Signed by me this 23d day of January, A. D. 1874.

A. D. JUDD.
